(57) **CLAIM**

The ornamental design for audio video system furniture, as
shown and described.

DESCRIPTION

FIG. 1 is a perspective view of a first embodiment of the
subject audio video system furniture;

FIG. 2 is a front plan view thereof;

FIG. 3 is a rear view thereof;

FIG. 4 is a right side view thereof (the left side being a
mirror image of the right side view)

FIG. 5 is a top plan view thereof;

FIG. 6 is a perspective view of a second embodiment of the
subject audio video system furniture; and,

FIG. 7 is a top plan view of the embodiment shown in FIG.
6 (all other views of the second embodiment having the
same appearance as FIGS. 2, 3 and 4).

1 Claim, 6 Drawing Sheets
